BRACKET FOR AN OVERHEAD DOOR ASSEMBLY

John C. Williams, Columbus, Ohio, assignor to
Kinnear Corporation, Columbus, Ohio

Filed Sept. 11, 1969, Ser. No. 19,119

Term of patent 14 years

Int. Cl. D8—03

U.S. Cl. D8—233

FIG. 1 is a perspective view of a bracket for an overhead door assembly embodying my design;

FIG. 2 is a side elevational view of the bracket as seen from the side opposite that shown in FIG. 1; and

FIG. 3 is an end elevational view of the bracket as seen from the right side of FIG. 2.

I claim:

The ornamental design for a bracket for an overhead door assembly, substantially as shown.
